(57) **CLAIM**

The ornamental design for vest for securing catheters as shown and described.

DESCRIPTION

FIG. 1 is a top view of a first embodiment of a vest for securing catheters in an unfolded configuration, showing the design;

FIG. 2 is a bottom view thereof in the unfolded configuration;

FIG. 3 is a top view thereof in a first folded configuration;

FIG. 4 is a top view thereof in a second folded configuration;

FIG. 5 is a perspective view thereof in a third folded configuration;

FIG. 6 is a side view thereof in the third folded configuration;

FIG. 7 is a perspective view thereof in the third folded configuration, and showing the environment;

FIG. 8 is a top view of a second embodiment of a vest for securing catheters in an unfolded configuration, showing the design;

FIG. 9 is a bottom view thereof in the unfolded configuration;

FIG. 10 is a top view thereof in a first folded configuration;

FIG. 11 is a top view thereof in a second folded configuration;

FIG. 12 is a perspective view thereof in a third folded configuration;

FIG. 13 is a side view thereof in the third folded configuration; and,

FIG. 14 is a perspective view thereof in the third folded configuration, and showing the environment.

The broken lines depict portions of the vest for securing catheters that form no part of the claim. The broken line showing of a human figure and catheter portion in FIGS. 7 and 14 show the vest for securing catheters in a condition of use and form no part of the claimed design.

1 Claim, 14 Drawing Sheets
